INVENTOR.

Mark Dean

BY

W. P. Proble

ATTORNEY.

UNITED STATES PATENT OFFICE.

MARK DEAN, OF BOONVILLE, NEW YORK.

VISE.

Application filed July 21, 1921. Serial No. 486,461.

To all whom it may concern:

Be it known that I, MARK DEAN, a citizen of the United States, and a resident of Boonville, Oneida County, and State of New York (whose post-office address is P. O. box 272, Boonville, N. Y.), have invented certain new and useful Improvements in Vises, of which the following is a specification.

10 The object of my invention is to provide a vise of simple, strong and peculiar construction by which pipes, tubing, rods, and other cylindrical objects, of different sizes may be received and firmly held and readily 15 released without injury to the pipe or other article so received and held.

My improved vise is not only capable of indefinite adjustability to different sizes, but the limit of closing of the gripping jaws is 20 automatically determined and secured by the pipe, tube, rod, or other article, itself without any biting or other injurious contact with the material of said pipe or other object.

25 One form of my invention is shown in the accompanying drawings in which:—

Figure 1, is a side elevation.

Figure 2, is a top plan.

Figure 3, is a longitudinal section to dis- 30 play the eccentrics and the limiting bar.

Figures 4, 5, 6, and 7, are detail views of one of the limiting bars, G, G'.

Same letters indicate similar parts in the different figures.

35 A is a suitable base upon which the vise is mounted. This vise consists, primarily, of two revoluble cylinders B, C, mounted respectively on pins b, b', in the uprights a, a', rising from the base A.

40 The size and shape of cylinders B, C, vary with the number of different sizes of pipes or other articles which are to be treated by the aid of the vise. Obviously, the greater variety of sizes the larger will be 45 the periphery of the cylinders. This periphery is provided with a number of receiving and gripping depressions, D, D', which vary to correspond with the various articles to be received and held by said vise

50 from the smallest which, as shown, is $\frac{1}{8}$ inch to the largest which, as shown, is one inch pipe.

It will be understood that the depressions D, will be so arranged on the cylinder B, 55 as to register with the depressions D', on the disk C, when the cylinders are turned

into position to receive the pipe. The cylinders are free to revolve independently, or may be geared together to rotate simultaneously, if preferred. The rear end of the pin b', is preferably square to enable it to be turned by a handle placed thereon, and by which handle the cam F, an integral part of the pin b', is thrown forward or backward, to bring the disk C toward or 60 away from the cylinder B, to secure the grip or release of the pipe held between the registering depressions.

The features so far described are all that will be necessary to enable my improved 70 vise to receive and hold pipes of the desired size. In such case the operation will consist of turning the two cylinders so that the proper sized depressions will register 75 their lower edges while their upper edges are far enough apart to receive the pipe from above; the pipe will be placed in the mouth thus formed by the openings and allowed to drop on to the limiting bars G,

G' and then the cylinder C will be thrown 80 into gripping contact to hold the pipe. After the work desired has been done on the pipe, the jaws will be opened by a reverse motion of the cam F, which will release the pipe. In this use of my improved 85

adjustable vise, however, the gripping depressions would not secure a perfect hold upon the pipe unless the pipe was exactly centered before it was gripped. If the pipe 90

in falling lie a little above or below the center, the pressure would cause the pipe to shoot up or down respectively. To avoid this, I introduce adjustable limiting bars 95

G, G', which are loosely hung on the two eccentrics H, H', of the cylinders B, C, respectively. Each eccentric is so shaped that its limiting bar rises and falls to levels which correspond to the sizes of the different depressions D, D'.

When properly adjusted, the limiting bar always occupies a position sufficiently below the opening between the lower edges of the registering depressions that the pipe to be held, on contacting with said bar, assumes a position with its center slightly below the center of pins b, b', and therefore all tendency to shoot upward as the gripping takes place is counteracted and a perfect hold is secured on the pipe.

To guard against breakage which might 110 result to the limiting bar, if the cylinders B, C, should not turn in unison, I have

made what in my earlier machine was a single limiting bar, into two pieces or halves, G, G', each of which is a duplicate of the other, and consists of an eccentric strap, and a tongue with an elevated portion to act as a rest for the articles gripped. These tongues ply in the openings, l, l', whenever the cylinders B, and C, are rotated.

10 I claim:—

1. A vise which comprises a suitable base; uprights arising therefrom a pair of revoluble cylinders mounted upon said uprights, said cylinders having peripheral gripping depressions of various sizes, adapted to register with their corresponding de-

pressions to grasp and hold the article to be treated while held in said vise, and a rev-

oluble cam adapted to move one of said cylinders toward and from the other to 20 form or release the grip on said article.

2. A vise which comprises a pair of revoluble cylinders having peripheral gripping depressions of various sizes, adapted to register their corresponding depressions to 25 grasp and hold the article to be treated while held in said vise, and a two-part limiting bar; each half of which automatically assumes the desired level below the opening between said corresponding depressions and 30 causes said article to position itself to receive the gripping pressure therefrom.

MARK DEAN.
